Primary Examiner — Sandra Snapp*Assistant Examiner* — Salamah Jordan(74) *Attorney, Agent, or Firm* — Timothy T. Wang;
Panorama IP GROUP(57) **CLAIM**

The ornamental design for a curved track climber machine as shown and described.

DESCRIPTIONFIG. 1 is a rear perspective view of a curved track climber machine showing my new design;
FIG. 2 is a front and lower perspective view thereof;
FIG. 3 is a right side elevational view thereof;
FIG. 4 is a left side elevational view thereof;
FIG. 5 is a rear elevational view thereof;
FIG. 6 is a front elevational view thereof;
FIG. 7 is a top plan view thereof;
FIG. 8 is a bottom plan view thereof;
FIG. 9 is an enlarged detail view of a portion of the curved track climber machine shown in FIG. 1;
FIG. 10 is an enlarged detail view of another portion of the curved track climber machine shown in FIG. 1;
FIG. 11 is an enlarged detail view of another portion of the curved track climber machine shown in FIG. 1;
FIG. 12 is an enlarged detail view of another portion of the curved track climber machine shown in FIG. 1; and,
FIG. 13 is an enlarged detail view of another portion of the curved track climber machine shown in FIG. 1.

The broken line showing of the curved track climber machine is included for the purpose of illustrating portions of the environmental structure and forms no part of the claimed design.
